UNITED STATES PATENT OFFICE

CHARLES D. CUMMINGS, OF TULLY, NEW YORK, ASSIGNOR OF TWENTY-FIVE PER CENT TO LEO E. FULLER, OF SYRACUSE, NEW YORK, AND FORTY-NINE PER CENT TO ALEXANDER F. FULLER AND CHARLES A. ALLEN, BOTH OF PORTSMOUTH, NEW HAMPSHIRE

PORTABLE CAN OPENER

Application filed April 9, 1927. Serial No. 182,385.

This invention relates to improvements in can, bottle and jar openers.

The main object of the invention is to provide means whereby the cover of a can may be removed by making a circumferential cut around the top of the can immediately below the locking seam of the can.

Another object of the invention is to provide means whereby the vacuum seal of bottles and jars may be broken easily and without injury to the container or its top.

Other objects and advantages relate to the details and form of the device as will more fully appear from the following description taken in connection with the accompanying drawings, in which:

Figure 1 is a top plan view of a device of this invention showing in dotted lines a jar top in position for opening.

Figure 2 is a side view, partially in section, showing in dotted lines a can in position to be opened.

In the figures the same numbers are used in referring to any given part of my device.

The construction of my device will be readily understood from the following description:

The device may be made of any suitable material and finished or decorated in any desired way. Bottom plate —1— carries at its forward end a cutting wheel —2— revolvably mounted thereon by means of a pivot pin —3—, said wheel having a beveled cutting-edge —4—. The top plate —5— carries at its forward end a driving wheel knurled on its periphery —6— and revolvably mounted on a pilot pin —7— sufficiently long to project through a slot —8— in bottom plate —1— and hold the driving wheel —6— immediately beneath the bottom plate —1—.

The slot —8— is slightly wider than the diameter of the pilot pin —7— and sufficiently long to allow longitudinal movement therein of such pilot pin —7— for approximately twice its diametric length. The cutting wheel —2— is made with a hub sufficiently long to maintain the cutting edge —4— in a plane immediately beneath the lower face of the driving wheel —6—.

The pilot pin —7— carries on its upper end

a frictionally tight wing nut —9— to permit of manually revolving the driving wheel —6—. The upper plate —5— is provided with a slot —10— through which extends a pilot pin —11— having a diameter slightly smaller than the width of the slot —10— and with a head larger than the width of the slot. The pilot pin —11— has its bottom end fastened in bottom plate —1—. The length of the slot —10— is approximately the same as the length of the slot —8— and the diameter of the pilot pin —11— is approximately the same as the diameter of the pilot pin —7—. The rear end of the top plate —5— is fashioned into an open hook form —12— into which is articulated the hook end —13— of the adjusting or actuating lever —14—.

The adjusting lever —14— is pivotally fixed to the bottom plate —1— by means of the fixed pivot pin —15—. The bottom plate is fashioned with a forwardly and laterally extending hook —16— adjacent to the pilot pin —15—. The upper plate —5— carries at its front end a laterally and rearwardly extending hook —17— of approximately the same size and shape as the hook —16—.

It will be seen that when the lever —14— is rocked upwardly (in Figure 1) about its pivot —15— it will exert force against the hook —12— and carry the bottom plate —5— forward, increasing the distance between the driving wheel —6— and the cutting wheel —2—, due to the fact that the cutting wheel —2— is stationary in the bottom plate —1— while the driving wheel —6— is carried forward with plate —5—, shaft —7— moving along the slot —8—. In the same way the distance between the hooks —16— and —17— will be increased. Conversely by the opposite movement of the lever —14—, the hook —13— of the lever —14— will engage with the hook —12— of the upper plate —5— and retract the plate —5— rearwardly and thus the distance between the driving wheel —6— and the cutting wheel —2— will be diminished, as will the distance between the hooks —16— and —17—.

When it is desired to open a can, the lever —14— is actuated sufficiently to permit the insertion of the upper rim of the can be-

between the driving wheel —6— and the cutting wheel —2— as may perhaps be better shown in Figure 2. The lever —14— is then actuated to decrease the distance between the two last mentioned wheels until the rim of the can is gripped with sufficient tightness so that the can will revolve when the driving wheel —6— is revolved by means of the wing nut —9— thereby causing the cutting wheel —2— to perforate the edge of the can and make a complete circumferential cut, thus removing the top.

When it is desired to open a vacuum sealed container, the device is actuated in the same way, the hooks —16— and —17— being inserted between the container and the container top, as perhaps may be better shown in Figure 1. The distance between the hooks is then decreased until the top of the container is sufficiently raised to permit entrance of air with the consequent destruction of the vacuum.

Altho I have shown and described a specific form and relation of parts as constituting an embodiment of this invention, I do not desire to restrict myself to the exact details of form or arrangement of the parts, as various changes and modifications may be made within the scope of the appended claim.

30 I claim:

In a device of the class described, a plate having a slot in one end, a cutting wheel rotatably mounted on the plate with its cutting edge adjacent the inner end of the slot, 35 a second plate, a shaft journaled in the second plate, a driving wheel on one end of the shaft, means for rotating the shaft, a hook formed in the other end of the second named plate, means for slidably mounting the second 40 named plate on the first named plate with the shaft positioned in the slot in the first named plate and between the cutting wheel and the outer end of the slot, a lever pivotally mounted on the first named plate, a hook at 45 one end of the lever articulating with the hook on the second named plate whereby the pivoting of the lever will move the driving wheel to and from the cutting wheel.

In witness whereof I have hereunto set my hand this 18th day of March, 1927.

CHARLES D. CUMMINGS.
